US0D1044183S

(12) **United States Design Patent** (10) Patent No.: **US D1,044,183 S**
(45) Date of Patent: ** Sep. 24, 2024

(54) **DUST COLLECTION STATION**

(71) Applicant: **Anker Innovations Technology Co., Ltd.**, Changsha (CN)

(72) Inventors: **Shihua Tang**, Shenzhen (CN); **Zongshuai Xu**, Shenzhen (CN)

(73) Assignee: **Anker Innovations Technology Co., Ltd.**, Changsha (CN)

(**) Term: **15 Years**

(21) Appl. No.: **29/853,263**

(22) Filed: **Sep. 14, 2022**

(30) **Foreign Application Priority Data**

Mar. 14, 2022 (CN) 202230130694.6

(74) Attorney, Agent, or Firm — Banner & Witcoff, Ltd.

(57) **CLAIM**

The ornamental design for a dust collection station, as shown and described.

DESCRIPTION

FIG. 1 is a front-top perspective view of a dust collection station showing our new design;

FIG. 2 is a rear-bottom perspective view thereof;

FIG. 3 is a front-bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the figures show portions of the dust collection station which form no part of the claimed design.

1 Claim, 9 Drawing Sheets
